UNITED STATES PATENT OFFICE.

GEORGE H. LONERGAN, OF LONGBEACH, CALIFORNIA.

DEVICE FOR PREVENTING THE CREEPING OF RAILROAD-RAILS.

1,009,674.

Specification of Letters Patent. Patented Nov. 21, 1911.

Application filed March 23, 1911. Serial No. 616,330.

To all whom it may concern:

Be it known that I, GEORGE H. LONERGAN, a citizen of the United States, residing at Longbeach, in the county of Los Angeles and State of California, have invented new and useful Improvements in Devices for Preventing the Creeping of Railroad-Rails, of which the following is a specification.

This invention relates to improvements in railroad chair plates and it is the object of the invention to provide a chair plate with securing means adapted to be fastened to the ties of a road bed, the said plate being also provided with rail gripping means for preventing the creeping of the rails of a railroad.

It is also the object of the invention to provide a chair plate which is adapted for use at the joint between the ends of meeting rails, the said plate having lateral projecting tie engaging portions and also having adjustable means for engaging and gripping the edges of rails superposed upon said plate.

In the drawing forming a part of this specification, Figure 1 is a perspective view of a portion of a railroad rail showing the improved chair plate and anti-creeping devices applied thereto. Fig. 2 is a top plan view of the chair plate. Fig. 3 is a transverse sectional view taken through the base of a rail and through the said plate taken upon the line of one of the gripping devices for preventing the creeping of the rails.

The details of the invention will now be more particularly described reference being had to the drawing in which 1 indicates a body portion of the chair plate forming the subject matter of the present invention. In order to adapt the plate 1 to its application to the ties of a road bed the said plate is provided at suitable intervals with laterally projecting portions 2 and 3 usually arranged opposite each other and provided with spike receiving apertures as 4. The plate 1 is preferably made for the greater portion of its length about the same width as the base or flange of the railroad rail that is to rest upon the same.

The apertures 4 are arranged to come just outside the edge of the rail flanges so that the spikes 5 which are driven into the ties and through said apertures 4 will be in position to engage the rail flanges in the usual way as will be apparent by reference to

Fig. 1. There may be one or more sets of projections 2 and 3 around the length of the chair plate 1, but two of such sets of projections are usually ample for the purposes required and are arranged to rest upon adjacent ties of the road bed.

The ends of the chair plate 1 project beyond the securing projections 2, 3 and are provided with upturned rail engaging flanges 6 formed integrally with the said plate 1. Opposite to the flanges 6 the plate 1 is preferably reduced in width as at 7 and is provided with a lateral extending screw as 8. The said screws 8 are adapted to receive removable clamp plates 9 having rail engaging flanges 10 adapted to extend inwardly over the edge of the plate 1.

In applying the chair plate in use it is usually slipped beneath the rails of a road bed and secured to the ties as above indicated. The chair plate is located so that the securing flanges 6 overhang the rail flanges after which the removable clamp plates 9 are slipped upon the screws 8 and one or more nuts 11 are employed upon said screws for drawing the clamp plates tightly against the flanges of the rail or rails. The reduced portion at 7 insures a tight gripping of the rail flanges since the material of the chair plate 1 will not interfere with the inward adjustment of said clamp plates. One or more nuts upon each screw 8 may be used as desired and the outer lock nut is generally employed in connection with the inner securing nut.

The chair plate is usually employed beneath the meeting ends of adjacent rails so as to thoroughly support the rail joints. The gripping devices carried by the said plate of which there are preferably always at least 2, so grip the rails as to prevent any creeping action in the same under the weight and movement of the rolling stock of the road. Such creeping action is possible because of the expansion spaces commonly allowed between the ends of the rails and when the adjacent ends of the rails are gripped by the improved chair plate forming the subject matter of this invention they are so held as to prevent the space being closed up by the endwise movement of the rails.

The adjustable gripping means employed permits of the rails being closed up by the endwise movement of the rails. The adjustable gripping means employed permits of

the rails being loosened at any time for ordinary repairs or renewals. The connecting of the meeting ends of the rails as above described is found to prevent the creeping 5 of the rails under the rolling action of trains passing over said rails.

What I claim is:—

1. A railroad chair plate, comprising an elongated rail receiving portion, means 10 near the ends thereof for gripping the ends of adjacent rails, comprising fixed flanges carried by the said elongated plate and movable flanges opposite thereto, bolt mechanisms projecting from said plates for 15 adjusting the movable flanges, the structure being such that the flanges at one end of the plate may be released when tamping or truing the rails and to allow for expansion and contraction thereof after which the 20 rails may be clamped again to hold the parts in adjusted positions.
2. A railroad chair plate having means for securing the plate to a plurality of ties

of a road bed and provided with rigid flanges for receiving the flanges of a rail and 25 oppositely projecting bolts and adjustable clamp plates engaging said bolts and adapted to force the rails against said rigid flanges.

3. A railroad chair plate comprising a 30 body portion capable of reaching past a rail joint having railroad rail engaging flanges, the said plate being reduced in width opposite said flanges and having threaded bolts 35 projecting therefrom, an adjustable clamp-jaw adapted to engage each threaded bolt, and nuts for forcing said jaws against the flanges of the rails to prevent the same from creeping.

In witness that I claim the foregoing I 40 have hereunto subscribed my name this 11th day of March, 1911.

G. H. LONERGAN.
